The ornamental design for a tripod, as shown and described.

DESCRIPTION

FIG. 1 is a front elevation view of a tripod showing my new design, with the legs fully extended;

FIG. 2 is a rear elevational view thereof;

FIG. 3 is a side elevational view with the legs partially extended and the third leg not shown for clarity;

FIG. 4 is a side opposite of that shown in FIG. 3 thereof;

FIG. 5 is a bottom elevation view with the legs extended;

FIG. 6 is a top elevation view with the legs extended; and,

FIG. 7 is a top perspective view with the legs retracted.

FIG. 1

FIG. 2

FIG. 3
